UNITED STATES PATENT OFFICE.

FRED L. MANNY, OF BENTON HARBOR, MICHIGAN, ASSIGNOR TO BAKER-VAWTER COMPANY, OF BENTON HARBOR, MICHIGAN, A CORPORATION OF MICHIGAN.

POSTING-STAND.

1,347,645.

Specification of Letters Patent. Patented July 27, 1920.

Application filed December 17, 1917. Serial No. 207,393.

To all whom it may concern:

Be it known that I, FRED L. MANNY, a citizen of the United States, residing at Benton Harbor, in the county of Berrien 5 and State of Michigan, have invented certain new and useful Improvements in Posting-Stands, of which the following is a specification.

My invention relates to a novel stand or 10 rack which I have devised for use by book-keepers and accountants in connection with a mechanical adding and listing machine of the kind commonly termed "posting machine," and used for posting items on the 15 ledger sheets of loose-leaf accounting systems such as are in extensive use in banks and commercial establishments of many sorts. The object of my invention is the provision of a convenient rack or stand to 20 receive and display the sheets from which entries are made on the ledger sheets by the machine, adjustable in all necessary respects, for the purpose of facilitating the work and lessening the number of movements necessary to get the ledger leaves and 25 the posting medium into position while making the entries on the ledger sheet. With this object and incidental advantages of construction and arrangement in view I 30 have devised and invented the structure hereinafter described, the essential elements of which are recited in the appended claims.

Of the drawings Figure 1 is a side view of my improved stand or posting 35 rack; Fig. 2 is a front view of the rack proper with the side plates in closed position; Fig. 3 is a similar view with the side plates extended; Fig. 4 a side view of the casting or block which supports the rack 40 plates, drawn on a relatively large scale; Fig. 5 is a detail, also on a relatively large scale, showing the form of the bracket secured to the center rack plate, and Fig. 6 is a detail showing the brackets carried by 45 the side plates and the set screws by which such brackets are secured to the supporting rod.

The same reference characters indicate 50 the same parts in all the figures of the drawing.

Before proceeding to a description of my novel posting stand, it may be explained that the stand is intended to sit between a

posting machine placed at one side, usually the left, and a loose-leaf binder or account 55 tray at the other side of the rack. The posting sheets, whether sales-slips, deposit-tickets, or sheets or books of whatever description, are thus displayed in the most convenient position for observation in making 60 entries.

To the base 1 of the rack structure is secured a hollow tube 2, within which the post 3 is arranged to telescope, a set screw operated by a hand-wheel 4 being provided 65 to lock the post at any desired position of adjustment of the rack up or down. The top of the post is threaded to engage a screw-threaded socket in a casting or block 5 which supports the rack members. This 70 casting is formed with a horizontal bore to receive a supporting rod 6, and a kerf is sawed from this bore to the outside of the block. A clamping screw 7 engaging a screw-threaded bore on one side of the kerf 75 and formed with an abutment bearing against the outer face of the casting on the other side of the kerf, the screw being equipped with a hand-wheel 8 by means of which it may be operated, serves to clamp 80 the rod 6 tightly in the bore of the casting.

The rack proper of my novel stand or 85 rack structure consists of a center plate and two side plates which are laterally adjustable and telescope with the center plate so that the width of the rack as a whole may be varied. The center plate 9 (see Figs. 2 and 3) is formed with a circular cutout space 9^a at its top, and the right-hand side plate 10 and left-hand side plate 11 are respectively formed with opposed cutout spaces 10^a and 11^a which lie back of the cut out space 9^a when such side plates are in innermost position, the edges of which last-mentioned spaces may register exactly with the edge of the space 9^a or 90 indifferently be concealed by the same if the cutouts 10^a and 11^a are made somewhat larger. The center plate and the left-hand side plate 11 are also cut away on 95 a slanting or diagonal line at the lower left-hand side of each, as indicated at 9^b and 11^b on the respective members. The center plate is formed with a forwardly extending flange 13 forming a shelf, the edge of which 100 is curved downward and backward to form

- a channel 14. The side plates 10 and 11 are arranged behind or to the rear of the center plate, and both are provided with forwardly extending flanges, marked 15 and 16 respectively, underlying the flanges 13 and at their forward edge slidably engaging the channel 14. The outside edge of the side plate 10 is also provided with a side flange 17 and the outside edge of the side plate 11 provided with a similar flange 18 extending from the cut 11^b to the top of the plate. Preferably, the plate 11 is stiffened by a strengthening strip 11^c welded to the back thereof.
- 15 The center plate 9 is equipped with a bracket 19 consisting of a strip of metal having a central portion welded or otherwise rigidly secured to the plate and side portions extending at a right angle thereto 20 which embrace the casting 5 and are orificed to engage the supporting rod 6 before mentioned. The side plates 10 and 11 are formed with brackets 20 similar to each other, each bracket being formed of a strip 25 of sheet metal bent to form a pair of bases 21 welded to the plate, sides 22 orificed to receive the rod 6, and a cross-portion 23 threaded to receive a set-screw 24 having a pointed end adapted to engage a longitudinal V-shaped groove 25 in the rod 6. As shown the cross portion 23 of the bracket 30 may be reinforced by a block 23^a welded thereto to afford a longer bearing for the set screw.
- 35 To provide for lighting the posting medium carried by the rack, the block or casting 5 has secured to it a hollow flexible arm 26 which carries a reflector 27 and socket for an electric lamp, the insulated conductors or cords 28 passing downwardly through the back hole of the block, which is recessed or chambered for the purpose as shown, and connected to any available source of lighting current.
- 40 It is obvious that my improved posting stand, constructed as above described, is exceedingly convenient and well adapted to the purposes in view. The rack may be adjusted to any desired height convenient to 45 the operator, whether sitting or standing, and may be extended to any width within its structural limits by adjusting the movable sides 10 and 11, the set screws 24 being manipulated to permit the adjustment to be accomplished and then tightened to 50 hold the parts in place. If narrow sheets are being used the sides can be brought together to just receive the sheets. In some cases it is desirable to arrange the posting 55 sheets at the left-hand side of the rack, and turn them over to the right, face down, and in the same order as they are posted, and the rack can be expanded to the right width to permit this to be done.
- 60 The cutout spaces at the top of the center 65

and side plates of the rack permit the user to reach down and easily get hold of the posting medium at the top, as may be most convenient in some cases, as when large single sheets are being posted from, while 70 the cutting away of the rack diagonally at its lower left-hand side not only enables the operator to get hold of the edge of the leaves at this point to turn them when it is desired to do so, but is particularly important in enabling the operator to reach 75 past the corner of the rack to manipulate the handle on the paper roll of the listing machine when inserting the ledger leaves. In case the operator is doing the work while 80 seated the height and position of the listing machine for convenient operation and of the posting stand for convenient observation are such that the cutting away of this corner is essential for practical use of the 85 stand.

It is necessary, in order to adapt the stand to be used with books and posting slips or sheets of paper of all degrees of weight and stiffness, as well as to suit the 90 desires of individual users, that the inclination of the rack should be capable of adjustment, and in the construction above described this may be attained by turning the hand-wheel 8 to unclamp the rod 6 and rotating the rack and rod as a unit in the block 95 5 to the desired position, and then clamping the rod securely in the block again.

I claim:

1. A posting stand comprising a standard, a horizontal supporting rod secured centrally to the top of said standard, a pair of side plates supported by said rod and laterally adjustable thereon, and a center plate telescoping with said side plates. 100
2. A posting stand comprising a standard, a block fixed to the top of said standard, a horizontal supporting rod rotatably mounted in said block and adjustably secured thereto, a pair of side plates laterally 105 adjustable on said rod, and a center plate telescoping with said side plates.
3. A posting stand comprising a standard, a block fixed to the top of said standard, a horizontal supporting rod rotatably mounted in said block and adjustably secured thereto, said rod being provided with a longitudinal groove, a pair of side plates 110 slidably mounted on said rod each equipped with a set screw engaging said groove, and a center plate telescoping with said side plates. 115
4. A posting stand comprising a standard, a block fixed to the top of said standard, a horizontal supporting rod mounted 120 in said block, a pair of side plates laterally adjustable on said rod, and a center plate engaging said block and telescoping with said side plates. 125
5. A posting stand comprising a stand- 130

ard, a block fixed to the top of said stand-
ard, said block being formed with a hori-
zontal split clamping bore and equipped
with a clamping bolt, a supporting rod
5 seated in said bore and formed with a lon-
gitudinal groove, a center rack plate pro-
vided with an orificed bracket engaging said
rod, and opposite side rack plates provided
with orificed brackets engaging said rod,
said brackets being equipped with set screws 10
arranged to engage said longitudinal groove
in the supporting rod.

FRED. L. MANNY.
